UNITED STATES PATENT OFFICE.

GEORGE S. FOLLANSBEE, OF BOSTON, MASSACHUSETTS.

WARPING-MACHINE.

SPECIFICATION forming part of Letters Patent No. 295,745, dated March 25, 1884.

Application filed July 11, 1883. (No model.)

To all whom it may concern:

Be it known that I, GEORGE S. FOLLANSBEE, of Boston, in the county of Suffolk, State of Massachusetts, have invented an Improvement in Warping-Machines, of which the following description, in connection with the accompanying drawings, is a specification, like letters on the drawings representing like parts.

This invention, relating to warping and beaming machines, has for its chief object improvements in the construction and adjustment of the drop-wires.

One part of my invention consists in expanding springs and means to operate them, combined with a series of dents, a series of heads positively connected with the said dents, and drop-wires pivoted to turn in the said heads fixed to the said dents, the latter being adapted to be moved toward or from each other, according as the expanding springs are contracted or expanded, substantially as will be described.

Other features of my invention will be hereinafter specified, and particularly set forth in the claims at the end of this specification.

Figure 1 represents in side elevation portions of a warping and beaming machine embodying my invention; Fig. 2, a section on the dotted line x x , Fig. 1, the support for the other end of the vibrator being shown in dotted lines, it in practice being just like the support at the left of the said dotted line in Fig. 1; Figs. 3 and 4, sectional details referring to the drop-wires and their supports and the slotted heads and dents; Fig. 5, a detail more extended, showing my invention embodied in an apparatus having but one row of drop-wires, the face of the box containing the usual expanding springs and screw being removed; Fig. 6, a cross-section of Fig. 5 on the dotted line x , the said Fig. 6 also showing, however, the vibrator-shaft with one set of arms; and Fig. 7 is a small diagram-like end view, to represent my improvements applied to a warping-machine of usual construction.

My present invention is incorporated with an apparatus such as shown in my application No. 78,808, filed December 8, 1882, and I have herein marked parts common to that application with like letters, and such parts do not therefore need to be herein specifically described, or the way of moving them be fully

shown. The parts common to that and this application are the vibrator or rock shaft b^3 , the cross-bar b^4 , having flanges, as therein described, the lever d^2 , having roller-tappets, rod e , bracket h^3 , and rod m^2 . The parts so far described will be operated as in the said application.

The vibrator-shaft b^3 (see Figs. 1 and 2) actuates two vibrators, A A , on arms A' A' , the said vibrators being adapted to strike the ends of any of the drop-wires B , which may drop into horizontal position by reason of the breaking of a thread, and the vibrator so arrested in its movement will effect the stopping of the machine, as described in the said application.

Referring to Fig. 7, the measuring-roller C , the drop-roller C' , the carrying-rollers C^2 C^3 , and the detaining-roller C^4 , for preventing slack in the threads between the measuring-roller and the drop-wires B , are or may be the same as those heretofore employed in warping-machines. The usual comb-box, D^3 , has within it a right-and-left-threaded screw, D^4 , to which are applied two traveling nuts, E , which, as shown in Figs. 1 and 2, are made to receive four pairs of usual expanding springs, E' E^2 E^3 E^4 , whereas ordinarily the said nut co-operates with but two pairs of expanding springs, as shown in Fig. 6. These expanding springs receive through them the dents 2, which at their upper ends have attached to them slotted heads 3. A series of these dents having been inserted between the coils of the springs, and their heads having been placed side by side with their openings 5 (see Fig. 4) in line, the other open end 6, of the drop-wires B are inserted into the slots of the said heads H , and the support 4 for the said drop-wires is then inserted through the said heads and the open rear ends of the drop-wires, as shown best in Figs. 2, 5, and 6. As the pairs of springs are expanded by turning the screw D^4 in the proper direction, the dents are uniformly separated, causing the heads and the drop-wires therein to slide laterally with relation to the support 4, which serves as the pivot for each drop-wire, and, besides serving as a pivot, the said support steadies the heads and dents and prevents the latter from being lifted out of the comb-box.

Instead of the support 4 being made as a

long rod, I may provide each head with a stout pin or pivot for the drop-wire to turn on.

To warp fine threads, there should be two rows of drop-wires, and it is an object to arrange them compactly. This I have done in Figs. 1 and 2, and in one comb-box, by enlarging the nuts E so that they may control expanding springs at each side, and by doing this I am also enabled to work the screw and nuts more uniformly than were the expanding springs connected only with one half of it, as in Fig. 6.

In Figs. 1, 2, and 6 I have provided means for lifting the drop-wires automatically, such means consisting of a long bar, 14, mounted on arms 15, pivoted at 16. Moving either of the said bars longitudinally from the dotted to the full line position, Fig. 1, elevates the bar and lifts the drop-wires, and vice versa. The lowest position of the bar 14 is governed by the arm 15, striking against a stop, 17. The rollers C C² C³ serve as supporting-rollers for the threads. Both ends of the bar 14 are supported by a like lever or arm, 15.

I claim—

25 1. The expanding springs and means to operate them, combined with a series of dents, a series of heads, 3, positively connected with the said dents, and drop-wires pivoted to turn in the heads fixed to the said dents, the said

dents being adapted to be moved toward or 30 from each other according as the expanding springs are contracted or expanded, substantially as described.

2. The comb-box, the right-and-left-hand-threaded screw, the nuts adapted to be actuated thereby, and two pairs of expanding springs at opposite sides of the said screw, combined with a series of dents held by the said springs, a series of heads positively connected with the said dents, and with drop-wires pivoted to turn 40 with relation to the said heads, substantially as described.

3. The dents 2 and the slotted head 3, rigidly attached to it, combined with a drop-wire pivoted in the said head, substantially as 45 shown and described.

4. The comb-box and series of pivoted drop-wires, combined with the bar 14 and its pivoted arms 15, to operate substantially as described.

In testimony whereof I have signed my name to this specification in the presence of two subscribing witnesses.

GEORGE S. FOLLANSBEE.
